C. SEEBERG

SKI BINDING

Filed Jan. 26, 1925

By *Clinton Seeberg*,
Brown, Townsend & Brickerstein,
Atlys.

Patented July 28, 1925.

UNITED STATES PATENT OFFICE.

CHRISTEN SEEBERG, OF OSLO, NORWAY.

SKI BINDING.

Application filed January 26, 1925. Serial No. 4,926.

To all whom it may concern:

Be it known that I, CHRISTEN SEEBERG, director, a subject of the King of Norway, residing at Skippergaten 36, Oslo, Norway, have invented certain new and useful Improvements in Ski Bindings; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to a ski binding of the type in which the toe part of the foot is fastened to the ski by aid of a clamping member gripping the edge of the boot sole. The known types of these bindings are in 20 themselves practical bindings, but they necessitate use of ski boots of exceptional solidity, in order to avoid that the soles or boots are impaired or wholly destroyed, the clamping members clamping the sole so 25 tightly to the ski, that the sole is subjected to a violent bending strain about a line between the back parts of the clamping members.

The object of my invention is to provide a 30 clamping device for clamping the sole to the ski by means of which the above named inconvenience is avoided, said clamping device comprising two clamping members, one on each side of the ski and movable longitudinally relatively to the ski. Preferably the 35 arrangement is such that the clamping members are imparted a combined swinging and sliding movement relatively to the ski. This clamping device may be combined with 40 a back binding of any suitable construction.

Two executional forms of the invention are illustrated in the accompanying drawings.

Fig. 1 is a side view partly in section 45 through a ski provided with a clamping device according to the invention.

Fig. 2 is a cross section on line II-II in Fig. 1.

Figs. 3 and 4 are, respectively, a side view 50 and a cross section of a modified form of the clamping device.

In all executional forms the ski binding is used in connection with stationary toe strap ears or lugs A, between which lugs the 55 toe part of the boot is inserted. These lugs A may be fastened in any suitable manner,

In the drawings the lugs are shown fastened by aid of screws (Fig. 2) screwed into the upper side of the ski, which is shown in longitudinal section in Fig. 1. On the upright part of the lugs A is arranged a clamping member C fastened to a bolt B sliding in an inclined slot H in the lug A. In the form shown in Figs. 1 and 2 the clamping member C has the form of an arm 60 to the rear part of which is linked a back binding F of leather or the like having preferably a tightening device G of known construction. The back binding and the tightening device form however no part of 65 this invention. The clamping members C are provided with ribs D extending inwardly from the lugs A and serving to grip above the upper face of the edge of the boot sole. The ribs D may be arranged at the 70 upper edge of the clamping member B or at the lower edge, or it may be arranged one such rib at the upper, and one at the lower edge of the clamping piece. In the latter case these two ribs grip the edge of the sole 75 between them.

The function of the binding is as follows:

The boot is first inserted between the rigid lugs A in such manner that the edges of the boot sole come beneath the gripping ribs D 80 of the clamping pieces C, said clamping pieces being thereby carried a little forwards. Thereupon the back binding is laid about the heel part of the boot and is tightened by aid of the tightening device G thereby drawing the clamping piece backwards, which owing to the bolt B following the slot 85 H is simultaneously lowered so as to clamp 90 the sole firmly against the ski.

Owing to the fact that the clamping arm 95 C is directly connected to the back binding the back part of the said clamping arm will be raised together with the back part of the boot during the operation, whereby a small 100 swinging movement is imparted to the gripping ribs D in such manner, that the sole is clamped more firmly to the ski with the forward ends but lift their backward ends a little, whereby the sole is allowed to bend more freely than heretofore. If the foot is bent 105 still more forwards in such manner that the front ends of the clamping arms C abut against the ski, the further movement of the back binding will be effected about the connection bolts between said back binding and 110 said clamping pieces. Instead of having the clamping pieces made in the form of arms

2

directly connected to the back binding, this connection may be effected by aid of an intervening connecting link. Such a modification is shown in Figs. 3 and 4, where the connecting links K are arranged on the outside of the stationary lugs A. The clamping piece C is in this instance provided with its clamping rib on its lower end and is connected with the connecting link K by aid of the bolt B sliding as in the former example in an inclined slot in the lug A. The connecting link K is at its other, backward end connected to an arm N, to which the back binding is fastened by aid of a bolt L. 15 This bolt L is guided in a slot M in the lug A.

The clamping pieces may also be arranged in such manner relatively to the guide slots that they can only be imparted a sliding movement and not simultaneously a swinging movement. This may for instance be obtained by providing the clamping piece with two bolts, both guided in the slot H.

As shown in Fig. 3 the clamping ribs of the clamping pieces may have a curved form.

Claims.

1. In ski bindings with rigid toe lugs the combination of clamping members for gripping the edges of the boot soles and pressing them against the ski, and a back binding connected to said clamping members, with guides for said clamping members in said lugs arranged so as to press the clamping parts of said clamping members against the sole on the back binding being tightened.

2. In ski bindings with rigid toe lugs the combination of clamping members for gripping the edges of the boot soles and pressing them against the ski, and a back binding connected to said clamping members, with inclined guide slots for said clamping members in said lugs arranged so as to press the clamping parts of said

clamping members against the sole on the back binding being tightened.

3. In ski bindings with rigid toe lugs the combination of longitudinally moveable clamping members for gripping the edges of the boot soles and pressing them against the ski and a back binding connected to said clamping members, with backwardly inclined guides in said lugs for said longitudinally moveable clamping members, said guides being arranged so as to press the clamping parts of said clamping members against the sole on the back binding being tightened.

4. In ski bindings with rigid toe lugs the combination of longitudinally moveable and turnable clamping members for gripping the edges of the boot soles and pressing them against the ski and a back binding connected to said clamping members, with backwardly inclined guides in said lugs for said longitudinally moveable and turnable clamping members, said guides being arranged so as to press the clamping parts of said clamping members against the sole on the back binding being tightened.

5. In ski bindings with rigid toe lugs the combination of longitudinally moveable clamping members for gripping the edges of the boot soles and pressing them against the ski and a back binding connected to said clamping members, with backwardly inclined guides in said lugs for said longitudinally moveable clamping members, said guides being arranged so as to press the curved clamping parts of said clamping members against the sole on the back binding being tightened.

In testimony that I claim the foregoing as my invention, I have signed my name 85 in presence of two subscribing witnesses.

CHRISTEN SEEBERG.

Witnesses:

MOGENS BUGGE,
GULBORG GULBRANSEN.
